United States Patent Office

Des. 177,817
Patented May 29, 1956

177,817

COMB OR SIMILAR ARTICLE

Lester Reute Kahn, deceased, late of Jersey City, N. J., by Alice Sabina Kahn, executrix, Jersey City, N. J., assignor to E. I. du Pont de Nemours and Company, Wilmington, Del., a corporation of Delaware

Application November 30, 1955, Serial No. 39,107

Term of patent 7 years

(Cl. D86—8)

Fig. 3

The characteristic features of this design reside in the portions shown in full lines.

What is claimed is:

The ornamental design for a comb or similar article, substantially as shown and described.
